UNITED STATES PATENT OFFICE.

ELISHA B. BRIDGMAN, OF BOSTON, MASSACHUSETTS.

REVERSIBLE SEAT.

SPECIFICATION forming part of Letters Patent No. 253,837, dated February 21, 1882.

Application filed October 21, 1880. (Model.)

To all whom it may concern:

Be it known that I, ELISHA B. BRIDGMAN, of Boston, in the county of Suffolk and State of Massachusetts, have invented a new and useful Improvement in Reversible Seats, of which the following is a specification.

This improvement is applicable to reversible seats for various purposes, and is especially adapted to seats and settees for chapel and hall use, horse and steam car seats, &c.

This invention relates to that class of reversible seats in which the seat proper will always incline or tip downward toward the back, whether it is reversed or not, thus greatly adding to the comfort of the occupants.

The nature of the invention is described hereinafter, and illustrated in the accompanying drawings, in which—

Figure 1 is a perspective view of a portion 20 of a seat embodying the improvement. Fig. 2 is a transverse vertical section of the same. Fig. 3 is a view of a portion of the seat with the parts separated. Fig. 4 is a longitudinal vertical section of one end enlarged.

Similar letters of reference indicate like parts.

a is the reversible back, swinging from the pivots *a'* upon the end pieces, *b*. The frame which connects the end pieces, *b*, consists of 30 two parallel longitudinally-placed bars, *c c*, provided at each end next the end pieces, *b*, with a cross-piece, *d*. Each cross-piece *d* supports a spring, *e*, whose upper end is secured to and supports a block, *f*. Each block *f* is provided 35 with a tenon, *f'*, which extends into a mortise or opening, *b'*, cut in the inner side of the end piece, *b*, next to said block. This opening *b'* is considerably larger than the tenon *f'*, for reasons which will hereinafter appear. 40 The seat *g* is supported by these two blocks *f*, and is provided on its under side with two parallel ribs, *h h*, corresponding with the bars *c c*, but a little nearer together.

The operation is as follows: When the back 45 is down, as in Fig. 1, it pushes the seat forward as far as the tenons *f'* can go in the openings *b'*, which brings the front rib *h* upon the front bar *c* and the rear rib *h* just forward of the rear bar. As soon as any person sits upon the seat its rear portion drops 50 upon the rear bar *c*, the rear rib *h* dropping just in front of said bar, while its front portion, of course, is raised the thickness of the front rib *h* above the front bar, *c*. Thus it 55 will be seen that when occupied the rear por-

tion of the seat is lowest, the front rib *h* supporting the front portion of the seat upon the front bar *c*, and the rear rib *h* acting as a stop to prevent the seat from slipping back or rattling, both the supporting-rib and the 60 rib acting as a stop performing their functions the entire length of the seat. If the back be raised, the springs *e* lift the seat and hold it level until the back is dropped, and if it is dropped upon the other side the effect is the 65 same, the then front rib resting on its bar *c* and the rear rib ready to drop in front of its bar *c* as soon as pressed down, by an occupant of the seat. When occupied, whether reversed or not, the rear portion or portion next the 70 back *a* is lowest, thus affording comfort to the occupant and avoiding any necessity of hollowing out the seat.

It will be seen that each rib *h* acts as a back stop and support alternately as the seat is reversed, while the ends of the mortises *b'* act as front stops to the seat through the tenons *f'*.

Cushions *k* are placed at various points to deaden the sound.

In practice the friction of the back in falling is usually sufficient to carry down the seat without the aid of the occupant.

Having thus fully described my improvement, what I claim, and desire to secure by Letters Patent, is—

1. In combination with the frame *b* and bars *c c*, extending from one end to the other of the settee, the back *a* and seat *g*, provided with the longitudinal ribs *h h*, extending the length of the seat and placed nearer together than 90 said bars, as shown, each rib acting alternately as a seat-support and back stop as the seat is reversed, substantially as and for the purpose set forth.

2. In combination with the frame *b*, provided with the relatively large openings *b'*, and bars *c c*, the seat *g*, provided with the ribs *h h*, blocks *f*, and tenons *f'*, substantially as and for the purpose described.

3. In combination with the bars *c c*, cross-bars *d d*, and springs *e e*, the seat *g*, provided with the ribs *h h*, and blocks *f*, provided with the tenons *f'*, and the frame or end pieces, *b*, provided with the large openings *b' b'*, arranged and constructed substantially as and 105 for the purposes specified.

ELISHA B. BRIDGMAN.
